UNITED STATES PATENT OFFICE.

ANGUS R. LE GRUE, OF BUFFALO, NEW YORK, ASSIGNOR OF ONE-HALF TO ALEXANDER S. FRASER, OF BUFFALO, NEW YORK.

WINDOW.

1,075,833.

Specification of Letters Patent. Patented Oct. 14, 1913.

Application filed June 20, 1911. Serial No. 634,819.

To all whom it may concern:

Be it known that I, ANGUS R. LE GRUE, a citizen of the United States, residing at Buffalo, in the county of Erie and State of New York, have invented new and useful Improvements in Windows, of which the following is a specification.

It is the object of this invention to provide simple, efficient and convenient means 10 for supporting window sashes while the same are swung from the window frame inwardly into the room and thus relieve the operator while the latter is cleaning the sashes.

15 In the accompanying drawings consisting of 2 sheets: Figure 1 is a perspective view of a window equipped with my improvements and showing the window sashes closed. Fig. 2 is a fragmentary vertical 20 transverse section, on an enlarged scale, in line 2—2, Fig. 1. Fig. 3 is a horizontal section in line 3—3, Fig. 1. Fig. 4 is a perspective view of the window equipped with my improvements and showing the sashes 25 turned inwardly.

Similar characters of reference indicate corresponding parts throughout the several views.

The window shown in the drawings for 30 illustrating my invention is constructed generally like those now in common use and comprises a frame having two upright jambs, 1, a sill 3, a head 4, inner, outer and intermediate stops 5, 6, 7 secured to each of 35 the jambs 1, upper and lower sashes 11, 12 sliding vertically in the outer and inner runways between said stops, and sash cords 13, 14 each connecting one of the sashes with a sash weight and running over a pulley 16 on one of the jambs. The two sash cords 13 connected with two of the corresponding vertical edges of a pair of sashes may be permanently connected therewith. The opposite vertical edges of both sashes 45 are detachably connected with the sash cords 14 on the opposite side of the window frame to permit of swinging these sashes from the frame into the room and back again into the frame. While the sash cords 14 are removed from the sashes the same are held in 50 such a position by engaging a knot 19 thereon with the underside of a fork 24 detachably mounted on the frame.

In order to support the sashes while they

are swung from the frame inwardly into 55 the room and thus relieve the operator of the weight of the sashes while cleaning the same a supporting device is provided which is preferably constructed as follows: 41 represents the body of a supporting rack 60 which preferably has the form of a rectangular frame and adapted to rest at its outer end upon the window sill by means of an outer short depending foot 42 projecting downwardly from the outer edge of the 65 body and resting on the sill of the window frame. In its operative position the body of the rack projects from the window frame inwardly into the room at right angles to the window or adjacent wall of the building. 70 The upper outer part of the body of the rack is detachably connected with the window frame by means of a retaining arm having an upright part 43 which is secured to one side of the body at the outer 75 end thereof and an upwardly and outwardly projecting or laterally off-set finger 44 arranged on the upper part of the upright bar and adapted to engage at its upper end with a shoulder 45 formed by the horizontal 80 upper inner stop of the window frame. The inner part of the rack body is supported upon the floor of the room by means of an inner long depending leg 46 secured at its upper end to the inner part of the body 85 while its lower end rests upon the floor. For the purpose of adapting this supporting rack to different heights of windows and to rooms in which the height of the window relatively to the floor differs the retaining 90 arm and inner long leg are made adjustable relatively to the body thereof. The means for effecting this adjustment may be variously constructed but the means shown in the drawings are suitable and comprise two 95 straps or loops 47 arranged on the body of the rack at the inner and outer ends thereof, one of these loops being adapted to receive the lower end of the adjustable retaining arm and the other the upper end of the long 100 supporting leg. This arm and the long supporting leg are pressed against the adjacent back side of the rack body or frame by means of clamping screws 48 arranged on the outer ends of these loops and bearing 105 against the outer sides of said arm and leg. By this means the retaining arm and long inner leg may be adjusted vertically on the

body of the rack so as to properly support the same on the head and sill of the window frame and upon the floor of the room.

At the lower edge of the body or frame of the rack the same is provided with two supporting arms 49 which form shoulders upon which the lower edges of the sashes are adapted to rest while the operator is cleaning the same. These supporting arms are 10 preferably pivoted on the lower edge of the rack body, as shown at 50, so as to permit of swinging the same horizontally and thereby folding the same against the underside of the rack body and enable the device 15 to be stored away more compactly when the same is not in use.

I claim as my invention:

1. A rack for supporting sashes while removed from the window frame, comprising 20 a frame adapted to be arranged at right angles to the window, a short outer foot depending from the lower edge of the rack frame adjacent to the outer vertical edge thereof and adapted to rest on the window 25 sill, a long inner foot depending from the lower edge of the rack frame adjacent to the inner vertical edge thereof and adapted to rest on the floor, an upper retaining arm 30 projecting upwardly and laterally outward from the upper edge of the rack frame adjacent to the outer vertical edge thereof and adapted to engage its upper end with a shoulder on the head of the window frame, and supporting arms arranged on the lower 35 edge of the rack frame and adapted to sup-

port the window sashes on the lower edges thereof.

2. A rack for supporting sashes while removed from the window frame, comprising a frame adapted to be arranged at right 40 angles to the window, a short outer foot depending from the lower edge of the rack frame adjacent to the outer vertical edge thereof and adapted to rest on the window sill, a long inner foot depending from the 45 lower edge of the rack frame adjacent to the inner vertical edge thereof and adapted to rest on the floor, an upper retaining arm projecting upwardly and laterally outward from the upper edge of the rack frame adjacent 50 to the outer vertical edge thereof and adapted to engage its upper end with a shoulder on the head of the window frame, and supporting arms arranged on the lower 55 edge of the rack frame and adapted to support the window sashes on the lower edges thereof, said short outer foot being fixed on the rack frame, said inner long foot being vertically adjustable on the rack frame, said upper arm being vertically adjustable on the 60 rack frame, and said supporting arms being pivoted on the rack frame to swing horizontally.

Witness my hand this 19th day of June, 1911.

ANGUS R. LE GRUE.
